UNITED STATES PATENT OFFICE.

BERTEL AAGE NIELSEN, OF KVISSEL, DENMARK.

APPARATUS FOR DISPLAYING LIGHT ADVERTISEMENTS.

1,407,564.

Specification of Letters Patent. Patented Feb. 21, 1922.

Application filed November 11, 1919. Serial No. 337,145.

To all whom it may concern:

Be it known that I, BERTEL AAGE NIELSEN, a subject of the King of Denmark, residing at Kvissel, Denmark, have invented a new 5 and useful Improvement in Apparatus for Displaying Light Advertisements, and I do hereby declare the following to be a full, clear, and exact description of the same.

This invention relates to apparatus for 10 displaying illuminated advertisement images. The apparatus comprises a rotatable picture carrying disk which is intermittently rotated by means of an electric motor, the disk being held stationary while the picture 15 or pictures are displayed and moved when the next picture in a succession of circumferentially arranged pictures is to be carried to the exhibition point. The lantern or lamp illuminating the pictures is put out 20 during rotation of the picture carrying disk. As many pictures as desired may be inserted in the disk, and the apparatus will completely fulfil the purpose of giving an interesting and effective advertisement.

25 A preferred form of the invention is shown on the drawing in which—

Figure 1 is an elevation of the apparatus,

Figure 2 is a plan view of the same,

30 Figure 3 shows part of a longitudinal section taken along the line $a-a$ in Fig. 2, and

Figure 4 shows in elevation a detail including a divided slide ring for closing and interrupting an electric circuit.

Within the frame of the apparatus is arranged 35 a small electric motor 1 which by means of suitable gear-wheels drives a crank 2 when the motor is supplied with current whereby a clock-work 3 forming another important part of the apparatus is wound 40 up. The clock-work and the electric motor are adapted to alternately impart turning movement to the crank 2 in a manner which will be further explained below.

The crank 2 is pivotally connected to a 45 pawl 4 engaging a ratchet-wheel 5 which is secured on a shaft 24 carrying at its forward end a picture disk 6. This disk is provided with a plurality of circumferentially distributed apertures 7 in which transparent or 50 translucent advertisement pictures may be inserted. When the crank 2 driven by the motor 1 is turned in a counter-clockwise direction from the position shown in Figure 3 the ratchet-wheel 5 is moved a tooth-distance 55 in the opposite direction of rotation, whereby the picture-disk 6 is also turned so as to

bring the next picture to the displaying point, that is to a position in the line between the illuminating lamp 12 and the lens 8. Fixed to the free end of the pawl 4 is a 60 cord 9 the opposite end of which runs around part of the circumference of a grooved roller 10 and is secured thereto. Fixed to the cord 9 and also to a point of the circumference of the roller 10 is one end 65 of a tension spring 11 the other end of which is attached to the frame. It may be remarked here that the roller 9 in operation performs only a slight angular movement to and fro. The roller 9 is carried by the 70 winding shaft of the clock-work 3 and the spring 11 constitutes the motive spring of this clock-work. Thus it will be understood that when the crank 2 is rotated as described above the clock-work is wound. When the 75 crank has performed approximately one half revolution so as to occupy a position substantially diametrically opposite to that shown in Figure 3 the supply of current to the motor is cut off, the disk 6 remains stationary during exhibition of the picture at the displaying point, and the stretched spring 11 is allowed to drive the clock-work and bring the tooth at the end of the pawl 4 to slide along the back of the ratchet wheel 80 tooth and engage the next tooth. When this is performed the exhibition of the picture which in the meantime has been illuminated by the lamp 12, is finished and the crank 2 and disk 6 are again driven by the motor 1, 90 whereas the flow of current through the lamp 12 is interrupted.

The alternating supply of current to the lamp 12 and the electric motor 1 is effected by means of a moving contact member in the 95 shape of a slide brush 13 attached to the crank shaft and revolving with the same. This slide brush constantly engages or slides against a complete ring of electrical conducting material counter-sunk into an insulating 100 member 14, the ring itself being not shown on the drawing. One conductor 15 of the two mains 15 and 21 is connected to this ring. The slide brush 13 also engages one or the other of two mutually insulated 105 electrical conducting members 16 and 17 forming together a divided ring which is arranged on an insulating member 18. The contact element 16 is by means of a wire 20 connected to the lamp 12 and the contact element 17 is by means of a wire 19 connected to the motor 1. The lamp 12 is 110

furthermore in connection with the main wire 21, while the motor 1 by means of conductor 22 is connected in series with a lamp 23, which serves as a resistance and may be arranged at some convenient place on the apparatus or at a distance therefrom. The lamp 23 is connected to the main wire 21. When the picture disk is being revolved the current flows from main 15 through the completer ring on insulating member 14, slide brush 13, contact element 17, wire 19, motor 1, wire 22 and lamp 23 to the other main 21. The motor is then running as long as the brush 13 slides against the contact element 17. When the brush leaves this element the flow of current through the motor and the lamp 23 is interrupted, and the further movement of the brush in engagement with the other contact element 16 is effected by the spring 11 which rotates the crank 2 in the manner described above. During this latter movement of the brush the current flows from main 15 through the complete contact ring on insulating member 14, brush 13, contact element 16, wire 20 and lamp 12 to the other main 21. The picture disk remains stationary and the picture at the displaying point is exhibited by being illuminated from the lamp 12.

30 When the spring 11 is bringing the pawl 4 to engage the next tooth of the ratchet wheel 5 it is desired that the crank 2 shall be released from the motor 1. For this purpose, a suitable clutch not shown on the drawing is inserted in the moving parts between crank and motor, the clutch being constructed to transmit motion from the motor to the crank but to slip when the crank tends to rotate the motor. A similar clutch 35 is arranged between the shaft for the roller 10 and the other parts of the clock-work 8, this latter clutch being adapted to slip when the spring 11 is strained through the action of the crank 2.

Having thus fully described my invention, 45 I claim as new and desire to secure by Letters Patent:

1. An apparatus for displaying illuminated advertisement pictures, comprising a rotatable disk adapted to carry a series 50 of circumferentially arranged pictures, a ratchet wheel revolving with the said disk, a pawl engaging the ratchet wheel and connected to a crank, an electric motor for rotating said crank, an electric lamp for 55 illuminating said pictures when at the displaying point, means for cutting off the flow of current through said lamp when said disk is being rotated, means for cutting off the flow of current through said motor when 60 the lamp is supplied with current and means for causing said pawl to engage another tooth of the ratchet wheel during stand-still of the said motor and disk.

2. An apparatus for displaying illuminated advertisement pictures as indicated in 65 claim 1, in which the said pawl is connected to a clock-work and serves for winding up the latter when the said crank is driven by the electric motor, the clock-work on the 70 other hand serving to cause the pawl to engage another tooth of the ratchet wheel during stand-still of the said electric motor and disk.

3. An apparatus for displaying illuminated advertisement pictures as indicated 75 in claim 1, in which a contact element rotating with the said crank moves in electric conducting engagement with two stationary contact rings one of which is a complete ring 80 and the other divided into two mutually insulated parts, for the purpose described.

In testimony whereof I have affixed my signature in presence of two witnesses.

BERTEL AAGE NIELSEN.
